UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,277,426.

Specification of Letters Patent. Patented Sept. 3, 1918.

Application filed September 11, 1914. Serial No. 861,205.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches.

One of the objects of the invention is to provide a simple and efficient snap switch mechanism particularly adapted for pull- 15 cord operation.

Other objects and advantages will appear hereinafter in connection with the description of a preferred embodiment of the invention illustrated in the accompanying drawing, in which—

Figure 1 is a plan view of a switch mechanism and supporting base, with a casing therefor shown in dotted lines.

Fig. 2 is a sectional view on the line 2—2, 25 Fig. 1, showing in addition another part of the base; and,

Fig. 3 is an exploded view of the switch mechanism and bases.

The mechanism illustrated comprises in 30 general a contactor 1 continuously rotatable in one direction with an intermittent snap movement under the influence of an energy storing operative connection with an oscillatory operating member 2 to make and 35 break circuit between stationary contacts 3 and 4 mounted upon an insulating base 5.

Referring more specifically to the drawing, the base 5 has a circular recess 6 within which the parts of the switch mechanism 40 are mounted. The bottom of this recess is provided with a plurality, in this instance four, of equidistant raised portions 7 having flat upper surfaces and sheer sides and constituting stops for the contactor, as will appear hereinafter. The stationary contacts 3 and 4 are positioned on opposite sides of the recess 6 between two stops 7 and are preferably upturned at one end, as at 8, to lie flush with the upper surface of the 45 adjacent stop. The contactor 1 is preferably of stamped metal and of a conformation shown in Fig. 3. It comprises a central portion 9 having four equidistant radial lugs 10, two of which are extended into resilient 55 arc portions having at their extremities off-

set contact surfaces 11. The lugs 10 are designed to serve as ratchet teeth and are engaged by a circular pawl member 12 having four equidistant and slightly offset pawls 13. The member 12 is mounted concentrically 60 with member 1 and is resiliently held thereagainst by a helical spring 14 having one extremity restrained between lugs 14^a on the pawl member and having its other extremity bent at right angles in the direction of its axis to be received within a marginal aperture 15 of the oscillatory operating member 2. This operating member has a radial extension 16 with a suitable catch for receiving a pull operating cord or chain 70 17. A second helical spring 18 has one extremity extended radially to interlock with the extremity of the spring 14 which passes through the operating member, and has its other extremity bent diametrically to rest 75 within a slot 19 of a threaded spindle 20, which passes through the base 5 and the aforesaid parts of the switch mechanism for securing the same in position on the base. A nut 21 threads on the end of the spindle 80 20 to prevent disarrangement of the movable elements. As shown the operating member 2 is provided with three of the marginal apertures 15, in any one of which the upturned end of the spring 14 is adapted to 85 fit. By this means the normal tension of the springs 14 and 18 may be easily regulated.

An insulating base 22 is also provided as complementary to the base 5 and is attached thereto for completing the inclosure of the 90 switch mechanism. Both bases are provided with cutaway portions 23 at one side which give clearance for the operating arm 16 and the pull chain 17 to swing as the switch mechanism is actuated. The stationary contacts 3 and 4 are held in position by integral riveting as shown in Fig. 2 and the contact 4 is connected with a binding post 24 at one side of the insulating base while the other contact is connected by a screw passing 95 through an aperture 25 to a second binding post 26 mounted on the opposite side of the base. Two other screw holes 27 are provided through the base parts to receive additional screws for completing the connection thereof.

Referring to Fig. 1 where the contactor 1 is shown as bridging the stationary contacts 3 and 4 the operation of the mechanism is as follows when the pull chain is operated: 100 110

The operating member 2 rotates clockwise and thereby tensions both the spring 18 and spring 14 and consequently tends to rotate the contactor 1 also in a clockwise direction. 5 The latter is restrained against movement, however, by the abutment of the offset contact surfaces 11 against the upturned ends 8 of the stationary contacts. This restraint of the contactor is maintained until the energy 10 stored in the spring 14 is sufficient to overcome the resilient and inherently releasable lock of the contactor, whereupon the same is snapped ahead until the contact surfaces 11 abut the next pair of raised insulating 15 stops 7 on the base 5, during which time the energy stored in the spring 14 is substantially dissipated. It is to be noted that during this movement of the contactor circuit is broken from the stationary contacts 20 through substantially 90° and that this distance includes both circumferential and axial movements of the contact surfaces 11. Upon release of the operating member the same is returned to initial position under 25 the influence of the spring 18, which also, by the other spring 14, turns the pawl member 12 in a counter-clockwise direction and back-ratchets the pawls 13 over the radial lugs 10 of the contactor. During the initial portion 30 of this returning movement, the contactor is itself moved slightly in a counter-clockwise direction until the depressed ends 11 thereof abut the insulation of the raised stops 7 which brace the bent ends 8 of the stationary contacts. The next operation of the 35 switch causes the contactor to rotate ahead with a snap movement in a manner identical to that described, but this time to bridge the stationary contacts and close circuit. It is 40 to be noted that the stationary contacts 3, 4 are maintained bright by a wiping engagement with the contactor both during the making and breaking of circuit and that by providing the upturned ends 8 of the stationary contacts it is insured that circuit 45 remains closed until accelerated movement of the contactor actually begins. Furthermore, the break is very wide and the mechanism is accordingly capable of efficient use 50 for controlling currents of relatively high value.

As shown in Fig. 1, a suitable metallic casing comprising a cap 28 and shell 29 is provided for housing the switch mechanism. 55 In practice, the cord 17 is preferably of a non-conducting material so that special insulation of the cord from the switch mechanism is rendered unnecessary.

What I claim as new and desire to secure 60 by Letters Patent is:—

1. In an electric switch, in combination, a stationary contact, a coöperating rotatable contact having parts tending to hold the same in circuit making and breaking position, an oscillatable ratchet member engag-

ing said contact member to rotate the same unidirectionally for circuit making and breaking, an operating member and an energy storing operative connection between said operating member and said ratchet 70 member to insure a snap movement of said rotatable contact upon leaving and reengaging said stationary contact.

2. In an electric switch, in combination, a stationary contact, a rotatable coöperating contact having parts tending to lock the same in and out of engagement with said stationary contact, an oscillatable ratchet member engaging said rotatable contact, to rotate the same unidirectionally for engagement and disengagement of said stationary contact, an oscillatable operating member and an energy storing operative connection between said operating member and said ratchet member to insure snap movement of 80 said rotatable member in leaving and reengaging said stationary contact.

3. In a pull switch, in combination, a stationary contact, a rotatable coöperating contact having parts to releasably lock the 90 same in and out of engagement with said stationary contact, an oscillating ratchet member coacting with said rotatable contact to rotate the same unidirectionally for engagement and disengagement of said stationary contact, an oscillatable operating member, an energy storing operative connection between said operating member and said ratchet member effective by its stored 95 energy to overpower the locking parts of 100 said rotatable contact and a return spring for said operating member.

4. In a pull switch, in combination, a base, a contact fixed thereon, a stud fixed to said base, a contact rotatably mounted 105 upon said stud to coöperate with said stationary contact and having parts tending to restrain the same in circuit making and breaking positions, a ratchet member oscillatably mounted on said stud to engage said 110 rotatable contact to move the same unidirectionally to engage and disengage said fixed contact, a pull operating member also oscillatably mounted upon said stud, an operative connection between said operating 115 member and said ratchet member comprising an energy storing spring coiled about said stud and a return spring for said operating member also coiled about said stud, said operating member when moved against 120 the action of its return spring effecting through said connecting spring and ratchet member a snap movement of said rotating contact both when leaving and reengaging said stationary contact.

5. In an electric switch, the combination with a rotatable contact, of an operating member therefor, an energy storing connection therebetween and a base having a plurality of conducting and non-conduct- 130

ing bearing surfaces for said contact disposed alternately in a common plane and each terminating in a relatively abrupt shoulder to releasably restrain operation of 5 said contact member pending storage of energy in said connection sufficient to effect release of said contact and movement thereof with a snap action for engagement with said conducting and non-conducting surfaces alternately.

6. The combination with a rotatable contact having a resilient extension, of an operating member therefor, an energy storing connection therebetween and a base having 15 a plurality of conducting and non-conducting bearing surfaces for the extension of said contact disposed alternately in a common plane and each terminating in a relatively abrupt shoulder, coöperating with 20 said contact extension to releasably restrain operation of said contact pending storage of energy in said connection sufficient to effect release of said contact and movement thereof with a snap action for engagement with 25 said conducting and non-conducting surfaces alternately.

7. In an electric switch, the combination with a rotatable contact, an oscillatable ratchet member for engaging said contact 30 to rotate the same unidirectionally, an operating member, an energy storing operative connection between said ratchet member and said operating member and a base having a plurality of conducting and non- 35 conducting bearing surfaces for said contact disposed alternately in a common plane and each terminating in a relatively abrupt shoulder to releasably restrain operation of said contact pending storage of energy in 40 said connection sufficient to effect release of said contact and movement thereof with a snap action.

8. In an electric switch, in combination, a rotatable contact having resilient extensions 45 on opposite sides of its pivot, an oscillatable ratchet member for engaging said contact to rotate the same unidirectionally, a pull operating member, an energy storing

operative connection between said ratchet member and said operating member and a base having a plurality of conducting and non-conducting bearing surfaces for the extensions of said contact disposed alternately in a common plane and each terminating in a relatively abrupt shoulder requiring deflection of the resilient extensions of said contact for movement of the latter between adjacent bearing surfaces and thereby restraining operation of said contact pending storage of energy in said connection sufficient to insure such movements of said contact with a snap action.

9. In a pull switch, in combination, a base, a contact fixed thereon, a stud fixed to said base, a contact rotatably mounted upon said stud to coöperate with said stationary contact and having parts tending to restrain the same in circuit making and breaking positions, a ratchet member oscillatably mounted on said stud to engage said rotatable contact to move the same unidirectionally to engage and disengage said fixed contact, a pull operating member also oscillatably mounted upon said stud, an operative connection between said operating member and said ratchet member comprising an energy storing spring coiled about said stud and a return spring for said operating member also coiled about said stud, said operating member when moved against the action of its return spring effecting through said connecting spring and ratchet member a snap movement of said rotating contact both when leaving and reëngaging said stationary contact, said contact having a relatively long range of unobstructed movement for producing a wide break in circuit upon leaving the contacting surface of said member.

In witness whereof, I have hereunto subscribed my name in the presence of two witnesses:

CHARLES J. KLEIN.
